UNITED STATES PATENT OFFICE.

ORTUS E. MOATS, OF CANTON, OHIO, ASSIGNOR TO THE AULTMAN COMPANY, OF SAME PLACE.

ROAD-SCRAPER.

SPECIFICATION forming part of Letters Patent No. 581,606, dated April 27, 1897.

Application filed October 12, 1896. Serial No. 608,618. (No model.)

To all whom it may concern:

Be it known that I, ORTUS E. MOATS, a citizen of the United States, residing at Canton, in the county of Stark and State of Ohio, have 5 invented certain new and useful Improvements in Road-Scrapers; and I do declare the following to be a full, clear, and exact description of the invention, such as will enable others skilled in the art to which it applies to make and use the same, reference being had to the accompanying drawings, and to the letters of reference marked thereon, which form a part of this specification.

Figure 1 is a side elevation of a road-scraping machine embodying my invention. Fig. 15 2 is a plan view. Fig. 3 is a vertical cross-section on the line $x-x$, Fig. 1, looking forward. Fig. 4 is a rear elevation showing the rear axle and the parts for adjusting it. Figs. 20 5 and 6 are detail views of a portion of the mechanism. Fig. 7 is a detail perspective view of the devices for shifting the blade laterally.

The operative parts of the mechanism are 25 supported upon a main frame, the principal parts of which consist of two longitudinal bars A A', these diverging somewhat from the front end toward the rear, and each being shaped so as to have a front upwardly-extending part a, an approximately horizontal central portion a', and a rear inclined part a², with a backward-projecting arm a³. These 30 main longitudinal bars are connected by cross-bars of any suitable number and character, such as that at a⁴ at the front end, that at a⁵ at an intermediate line, and others that 35 will be referred to.

The main frame is supported upon a running-gear comprising the front axle C, with 40 wheels D, and the rear axle C', with its wheels D'.

The front axle C is pivotally connected with the front end of the main frame, the latter having an expanded ring a⁶, which rests upon 45 a similar opposing ring c, carried by the axle and supported thereon by means of a standard c', there being a king-bolt of the ordinary sort for joining the parts together.

At the rear the main frame rests upon the

axle c' and is adjustably connected thereto in 50 the manner to be described below.

The platform upon which the operator stands is indicated by B, it being supported by the rear part of the main frame in a suitable position.

Upon the supporting and transporting devices referred to is arranged a scraper-blade E. This may be of any of the common forms or of any preferred sort. That shown is concavo-convex in cross-section and is substantially straight from end to end. It is connected by horizontal pivots to the draft-bars E', which are curved downward and secured to the rear side of the curved scraper-blade and extend forward over the top thereof on 60 converging lines to the part which carries them. The latter is indicated by F and consists of an expanded-ring-like plate, to which the aforesaid bars or arms E' are bolted.

The present construction differs from those 70 heretofore largely used, and has for one of its objects to simplify this part of the machine. In the earlier machines referred to use has been made of two rings or segments of rings which have required accurate fitting and have 75 increased the number and weight of the parts and the expense incident to their construction beyond what is desirable. In the present machine one of the two rings commonly used is dispensed with entirely. The scraper-supporting part at F is suspended and guided by means of two clips or flanged bolts G, one on each side, and a third clip or flanged bolt or lug G' at the front. These are so arranged as to greatly reduce the friction incident to 80 the movements of the scraper when again adjusted, and successfully obviate the expense incident to providing and fitting the second ring used in earlier machines. The clips or lugs G G' are secured to the draw-frame of 85 the scraper, the latter consisting principally of the bar or bars I and one or more cross-bars. As shown, there is a bifurcated bar I, having the backwardly-diverging arms i i' united at the front end, where there is an eye i', pivoted to an eye i², carried by the main frame at its front end. As a result, the 90

scraper and its supporting devices are al- 95

lowed all of the flexibility, motions, and adjustments which are incident to machines of this class, such as the vertical movements of either end of the scraper independently of the other or the vertical movement thereof uniformly from end to end, and the endwise swinging or adjustment of it on lines transverse to the machine, and, notwithstanding the direct connection of the supporting-plate to F immediately to the front bar I, instead of employing the heretofore common ring to carry this part F the rotary or axial adjustment of the blade is also readily effected.

The scraper and its draft-frame just described are suspended from the main frame as follows: J J are links, one at each side of the machine. H is a bar secured to the draft-bar I, extending transversely thereof and of the machine. Preferably it carries the two clips or flanged lugs G G', which support the scraper-plate F, as above described, and at its ends it has eyes h by which it is flexibly connected to the links J. The latter, at their upper ends, are hinged to vertically-adjustable plates K by means of the eyes k. The plates K have vertical bars K' with inwardly-turned rack-teeth and are fitted in guides l l. Preferably the latter are the upturned arms of a cross-bar L, rigidly secured to the frame-bars A A'. They have grooves in their outer faces to receive the rack-bars K' and have apertures or slots to permit the teeth of said bars to engage with the pinions M, by which the bars are moved up or down either simultaneously or independently of each other. The pinions M M are secured to shafts m m, which are mounted in bearings at m' m'. At the rear ends of the shafts m there are worm-wheels N, which engage with worms O. Each worm O is on a short shaft o, which carries at its inner end an expanded hand-wheel O' in proximity to the platform B.

It will be seen that the operator standing on the platform can at any time, by means of the hand-wheels O', readily cause the rotation of the pinions M M either independently or simultaneously and in either direction, and as a result can raise or lower either or both ends of the scraper-blade through its draft-frame.

In order to shift or adjust the blade laterally, I combine with it and with its support the following devices: S is a worm-wheel arranged horizontally and mounted on the shaft S², held by the bars s' s², secured to the main frame. This wheel carries a crank-arm S', which is connected by the link S³ to the scraper-frame. T is a worm meshing with the teeth of the wheel S and secured to shaft t. This shaft extends backward toward the operator's platform, and can be rotated by a hand-wheel T' thereon.

Heretofore the scrapers have been shifted from side to side or laterally adjusted by means of transversely-sliding rack-bars, with worms, bevel-gears, &c. One of the objects

of the present invention is here also to simplify the construction, reduce the number of parts, obviate the loss of power from friction and binding, and provide a simple adjusting device consisting practically of but a single piece—namely, the wheel S, with its crank-arm S'. The cramping and friction are almost entirely overcome, as the bearing-surfaces are reduced to that of the shaft S², which supports the wheel S, this being in contradistinction to the long bearing-surfaces required for the transverse sliding-bars in the earlier constructions. The arm S' vibrates with but little resistance, and the flexibly-connected link S³ applies all the power to throw the scraper to the right or the left.

The scraper-plate F can be adjusted axially—that is, rotated more or less around a vertical axis at the center of said plate to permit the varying of the working angle of the blade to permit its complete reversal—by means of a series of gear-teeth U, formed on the plate or on a bar secured thereto, a pinion U' and a shaft u, the latter being mounted in bearings carried by the draft-frame of the scraper. The shaft u is coupled to an inclined shaft U², which extends to a point near the platform and is provided with a hand-wheel U³, this shaft U being held in a bracket-carrier U⁴, which permits it to be swung to the right or the left without cramping. By means of these devices the operator can at any time cause the wheel U' to rotate the tooth portion of the plate F, and thus axially adjust or reverse the scraper-blade. The scraper and the plate F are locked in any position desired by means of the bolt or pin V. This is carried by a short arm on the rock-shaft v, mounted in bearings on the draft-frame. This shaft v is coupled at v³ to an extensible shaft v², which in turn is coupled at v⁵ to a rock-shaft v⁶, mounted on the platform and having a foot-piece or pedal v⁷. When the operator desires to adjust the scraper axially, he unlocks the plate F by placing his foot on the pedal v⁷, which raises the pin V out of its aperture, and, after effecting the adjustment, he removes his foot, whereupon the lock-bolt V drops into the opposing aperture and the scraper is held rigidly upon its draft-frame.

The rear axle can be adjusted relative to the longitudinal lines of the machine as follows: This axle is pivoted by a vertical bolt or pin at w at a point relatively near to one of the wheels D', the pivot preferably engaging with one of the side bars of the main frame. At a point near the opposite rear wheel adjusting devices are interposed between the main frame and the axle, these consisting of a threaded rod W and a nut w², the latter being connected to or formed with a bevel-wheel. With this wheel another at w' engages, the latter being secured to a vertical shaft W', which has at its upper end a hand-wheel w³, conveniently arranged for reaching from the platform.

Whenever the operator desires to have the axle at an inclination to the longitudinal lines of the machine or to vary such inclination for any of the now well-known purposes, he 5 can instantly effect such adjustment by rotating the hand-wheel w^3 , whereupon the nut and shaft at W w^2 cause the axle to be moved forward or back at its free end.

In respects other than those above recited 10 there can be modifications as concerns the details of the mechanism illustrated. Thus the rectilinearly-sliding plates or bars K and their tooth-elevating devices can be omitted and a simple crank extending outward from 15 the shaft n can be substituted for raising or lowering the links J. So, too, other means may be employed for effecting the axial adjustment or reversal of the blade; and, again, some of the features of the present mechanism 20 can be employed in those machines in which the scraper-blades are pushed from behind instead of being drawn from the front.

The worms O and the worm-wheel N not 25 only serve as a means for moving the scraper-blade up or down, but also as a positive lock for holding the vertically-adjustable parts in any position in which they are put.

By having the shafting for the lock V automatically extensible provision is made for 30 allowing the scrapers to swing laterally in either direction. This extension of the lock-shafting is provided by forming the intermediate section v^2 of two telescoping parts v^8 and v^9 , the latter being tubular and slotted, 35 and the part v^8 being connected by a pin therein fitting in the slot, as at v^{10} . This shafting has one section mounted on the scraper-support in fixed relations thereto, and one section on the platform or support- 40 frame, and a third section interposed between the two aforesaid and universally coupled to both of them, as at $v^3 v^5$. Consequently both the lock and the pedal-piece are kept in fixed relations to their supports, and yet the 45 lateral adjustment of the scraper is permitted.

What I claim is—

1. In a road-scraping machine, the combination with the main frame having front wheels and rear wheels, of the scraper-blade 50 and the draft-frame having one or more upwardly-bowed bars I immediately behind the front wheels, and the rear horizontal portions, the cross-bar H secured to the said horizontal portions, the depending flanged 55 clips or lugs G secured to said cross-bar, the clip or lug G' in front thereof, the circular plate F rotatably supported in the said clips or lugs, and the draw-bars E' secured to the plate F and to the scraper-blade, substantially 60 as set forth.

2. In a road-scraping machine, the combination with the supporting-frame and the laterally-adjustable scraper, of the horizontally-arranged wheel S having a crank-arm connected thereto, one or more links S³ connecting 65 said crank-arm to the scraper and gearing

controllable by the operator for rotating the said wheel S, substantially as set forth.

3. In a road-scraping machine, the combination with the supporting-frame and the 70 scraper, of the rotary plate F secured to the scraper and adapted to be adjusted axially, the lock for holding said plate in either of several positions, the shafting extending to the operator's platform for actuating the lock, 75 said shafting being automatically extensible, substantially as set forth.

4. The combination with the supporting-frame, and the scraper, of the intermediate adjustable draft-frame connected to the 80 scraper, and adapted to have the scraper adjusted thereon around a vertical axis, a lock for holding the scraper in either of several positions relative to the draft-frame, and shafting for actuating said lock, said shafting 85 having a section mounted on the draft-frame, a section mounted on the main frame, and means for universally coupling the two said sections, and said shafting being automatically extensible, substantially as set forth. 90

5. In a road-scraping machine, the combination with the main frame, the draft-frame, and the scraper, of the front running-gear, the rear axle pivoted relatively near one end to the main frame near one side thereof, the 95 horizontal threaded shaft W connected to the axle near the other wheel, the nut engaging with said shaft, the gearing for rotating the nut, and the vertical shaft for actuating said gearing and having at its upper end a crank 100 or hand-wheel adapted to be actuated from the platform, substantially as set forth.

6. In a road-scraping machine, the combination with the supporting-frame, the scraper draft-frame pivotally connected to the supporting-frame, and the scraper supported from said draft-frame and adapted to vibrate about a vertical axis independently of any movement of said frame, of a toothed wheel or disk pivotally mounted on the main frame, 110 a link connecting said disk with the scraper draft-frame, gearing controlled by the operator standing on the platform on the main frame for rotating said toothed wheel or disk and adjusting the scraper laterally of the 115 supporting-frame, substantially as set forth.

7. In a road-scraping machine, the combination with the supporting-frame, the scraper draft-frame pivotally connected to the supporting-frame, and the scraper-blade supported by said draft-frame, of a horizontally-arranged toothed wheel S mounted above the scraper, a link, S³, connecting said wheel and the scraper draft-frame, a shaft extending longitudinally of the supporting-frame and 125 having at one end a worm meshing with the teeth in the wheel S and at its other end a hand-wheel, substantially as and for the purpose set forth.

8. In a road-scraping machine, the combination with the supporting-frame, and the scraper-blade, of the rotary plate F secured

to the scraper and adapted to be adjusted axially, a lock for holding said plate and the blade stationary in either of several positions, a rock-shaft for moving said lock, a rock-shaft on the operator's platform, and an automatically - extensible connection between said rock-shafts, consisting of a tubular member, and a rod fitted loosely in said tubular member and having projecting pins or lugs

extending into guides formed in the tubular member, substantially as set forth.

In testimony whereof I affix my signature in presence of two witnesses.

ORTUS E. MOATS.
